UNITED STATES PATENT OFFICE.

EDWIN G. DANIELS, OF CHICAGO, ILLINOIS, ASSIGNOR TO CHICAGO BRIDGE & IRON COMPANY, OF CHICAGO, ILLINOIS, A CORPORATION OF ILLINOIS.

SPACING TABLE.

Application filed October 31, 1923. Serial No. 671,933.

To all whom it may concern:

Be it known that I, EDWIN G. DANIELS, a citizen of the United States, residing at Chicago, in the county of Cook and State 5 of Illinois, have invented a new and useful Improvement in Spacing Tables, of which the following is a specification.

This invention relates to improvements in spacing-tables or mechanism for feeding 10 sheet metal to punching-machines and the like. By means of my improved spacing-table it is possible to punch holes which are very accurately spaced. Although I have shown the spacing-table designed for operation 15 in connection with a punching-machine, it is obvious that without detracting from the spirit of the invention, the spacing-table may be used in connection with any other kind of machine designed to perform successive operations upon a piece of sheet metal 20 where it is necessary or desirable to feed the sheet metal to or through the machine so that the successive operations may be accurately spaced thereon. By the use of my 25 improved spacing-table it is possible to adjust the mechanism in advance so that successive holes may be easily and quickly spaced very accurately and exactly at a desired interval throughout the length of the 30 material. It is also possible with my improved spacing-table to very quickly set the mechanism so that practically any desired spacing interval may be obtained, the exact 35 distance between the holes being visible on a gage with which the table is equipped. Other features and advantages of my improved spacing-table will appear more fully 40 as I proceed with my specification.

In that form of device embodying the features of my invention shown in the accompanying drawings, Figure 1 is a top plan view of my improved spacing-table showing parts broken away, Fig. 2 is a similar view in side elevation, Fig. 3 is a transverse vertical sectional view taken as indicated by the line 3 of Fig. 1, Fig. 4 is a top plan view of the device with the table itself removed showing the spacing mechanism underneath, Fig. 5 is a view taken as indicated by the line 5 of Fig. 4, Fig. 6 is a longitudinal sectional view taken as indicated by the line 6 of Fig. 4, Fig. 7 is a vertical longitudinal sectional view showing the operation of one of the dogs forming a part of the 55 spacing mechanism, the view being taken as

indicated by the line 7 of Fig. 8, Fig. 8 is a view taken as indicated by the line 8 of Fig. 7, Fig. 9 is a view taken as indicated by the line 9 of Fig. 1 and Fig. 10 is a view taken as indicated by the line 10 of Fig. 9. 60

As shown in the drawings, A indicates in general a punch press in connection with which my improved spacing-table may operate. 12 indicates the punch head of the punch press carrying the punches 13 of 65 which there may be any desired number. It is obvious that any number of punches may be used at once. 14 indicates a rotatable shaft designed for reciprocating the punch head. These elements form parts of 70 an ordinary punch press and are no part of the present invention. Any kind of punch press may be used in connection with my improved spacing-table.

My table includes a long, rectangular, flat 75 table proper 20 suitably stiffened and supported by longitudinally arranged parallel angle-irons 21 attached to its under surface. The outer pair of angle-irons 21 have their depending flanges resting on the rollers 22 80 in order to make the table easily movable. It is to be noted that the rollers 22 on one side of the table are grooved to accommodate the flange of the angle-iron 21 and keep the table in alignment. Any desired means 85 may be utilized for moving the table. For example, it may be moved manually. I have here shown suitably supported at one side of the table a rack-bar 23 with a large gear-wheel 24 engaging with the teeth 90 thereon. Any suitable means (not shown) may be provided for driving the gear-wheel 24 in order to impart movement to the table.

Longitudinally extending and centrally arranged on the under side of the table, here 95 shown as supported by two of the members 21, are six rack-bars indicated as 24^a, 24^b, 24^c, 24^d, 24^e, and 24^f. Each of these rack-bars has downwardly projecting teeth regularly spaced throughout its length; but the 100 space between two adjacent teeth on each rack-bar is different. For example, the teeth on the rack-bar 24^a may be spaced one inch apart, those on the bar 24^b, 1½ inches apart, those on the next bar, 2 inches apart 105 and those on the next bars, 2½ inches, 3 inches and 3½ inches apart. It is obvious that the spacing of these teeth on one or more of the rack-bars may be as desired for the particular usages to which the mecha- 110

nism is to be put. These bars are preferably made detachable so that they may be quickly and easily removed and replaced by other bars with differently spaced teeth, if 5 desired.

Arranged below the rack-bars 24^a to 24^f are six dogs 25^a to 25^f inclusive, each adapted to cooperate with its corresponding rack-bar when in operative position. The following means are provided for placing any 10 one of the dogs 25^a to 25^f in operative position. I will describe in detail but one of the dogs and its associated parts, it being understood that there are six dogs in all, each operated in a similar manner. I will describe the dog shown in Fig. 7 which is indicated by 25^a and in connection with this dog where I use reference numerals followed by the letter "a," it is to be understood that 15 in each case, there are six similar parts, "a" to "f" inclusive, one for each of the corresponding dogs. Transversely arranged and rotatably supported at one side of the dogs 25^a to 25^f is a bar 26 having six flattened 20 portions thereon as indicated by 27^a to 27^f inclusive, one for each of the corresponding rack-bars. These flattened parts are spaced around the circumference of the bar 26, 60 degrees apart so that as the bar is rotated, 25 one at a time is at the under side. Arranged below the bar 26 are six pivoted levers 28^a to 28^f inclusive, one for each of the dogs 25^a to 25^f. The lever 28^a is pivoted at 29 as 30 shown and has one end bifurcated with the dog 25^a lying between the prongs. The ends of the prongs are rounded as indicated by 30^a and lie in recesses 31^a formed in the sides of the dog 25^a. The dog 25^a has a projection 32^a near its lower end to which it 35 attached a spiral spring 33^a which tends to pull it upwardly. The bar 26 lies just above the pivoted lever 28^a (see Fig. 7) and is so arranged that when the flattened place 27^a is on the under side, the bifurcated end 40 of the lever is permitted to rise sufficiently so that the dog 25^a at its upper end will engage the teeth of the corresponding rack-bar 24^a. When the bar 26 is rotated, 45 however, so that this flattened portion is not on the bottom side, the bifurcated end of 50 the lever 28^a will be depressed sufficiently to lower the dog 25^a so that it will be in inoperative position so that its upper end will not engage the teeth of the rack-bar 24^a. 55 It will be seen that with this construction, by rotating the bar 26^a so that any desired flattened part 27^a to 27^f will be on the under side, any desired dog 25^a to 25^f is permitted 60 to rise sufficiently to engage the teeth of the corresponding rack-bar, the other five dogs all being held down in inoperative position. The following means are provided for rotating the bar 26 in order to put any dog desired into operative position. The bar 65 26 (see Fig. 4) is extended out to the side of

the table and has on its end a bevel gear 35 meshing with another bevel gear 36 on the end of the longitudinally arranged shaft 37. The shaft 37 has its other end made hexagonal in shape as indicated by 38^a to 38^f inclusive 70 corresponding to the six faces of the hexagonal part. The following means (see Fig. 5) are provided for rotating the shaft 37. Mounted on this shaft is a gear wheel 40 meshing with an arcuate rack 41 controlled by lever 42. A scale 43 is provided and the parts are so arranged that movement of the rack 41 will rotate the shaft 37 one complete turn so that it may be moved to bring any one of the faces 38^a to 38^f upwardly. The corresponding dog thus put into position is indicated by the scale 43. It will be seen therefore that it, for example, the shaft 37 is so turned that the dog 25^a will be in operative position to engage with the rack-bar 24^a having its teeth spaced one inch apart that the table may be moved one inch at a time by allowing the dog 26^a to engage with the successive teeth on the rack-bar 24^a. The table is moved from right to 75 left as viewed in Figs. 1 and 6. If spacing 1½ inches apart is desired, the shaft 37 is turned with the face 38^b upwardly so that the dog 25^b will be put into operative position to engage with the rack-bar 24^b having 80 its teeth spaced 1½ inches apart. The mechanism also has a fine or vernier adjustment for obtaining spacings between those given by the rack-bars alone. In speaking, 85 therefore, of obtaining a spacing of one inch by use of the rack-bar 24^a, I assume that this vernier adjustment, which I will describe in detail later, is set at neutral. Likewise, in getting a spacing of 1½ inches by the use of the rack-bar 24^b which has its teeth spaced 100 1½ inches apart, I assume that the vernier adjustment is set at neutral. 105

It is obvious that in the operation of the device some means must be provided for disengaging the dog which is in use at the 110 time from the teeth on the corresponding rack-bar in order to permit successive movements of the table for successive operations of the punching-machine. I will now describe this means in connection with the dog 115 25^a, it being understood that there are similar means for each of the other dogs. Arranged below the levers 28^a to 28^f is a rotatable shaft 50 provided with six arms 51^a to 51^f corresponding to the six levers 28^a to 120 28^f. The shaft 50 extends transversely under the table and is provided at one end with an arm 52. Upward movement of the arm 52 will rock the shaft 50 to raise all the arms 51^a to 51^f inclusive. Five of the 125 dogs are being held down by the shaft 26 and consequently their corresponding levers 28 will not be engaged by the arms 51. Assuming that the dog 25^a is the one in operative position, it will be seen that the end of 130

the lever 28^a will be engaged by the arm 51^a to lower the dog 25^a when the shaft 50 is rocked. This rocking of the shaft 50 may be accomplished in any desired manner. 5 For example, after each punching operation, the arm 52 may be manually raised to lower the dog out of the notch in the rack-bar 24^a. Preferably, means such as the vertical shaft 55 are provided, adapted to be 10 operated by the machinery running the punch press to raise the shaft 55 after each punching operation and release the dog 25^a from the tooth in the rack-bar. It is to be noted that the dog 25^a (and the other dogs 15 likewise) is somewhat loosely mounted in the vertical slot in which it moves so that it can rock slightly. A stop 56^a is provided against which the dog bears when engaged by the tooth 57^a in the rack bar 24^a. The 20 movement of the table is thereby limited. When the dog is disengaged from the tooth 57^a, however, and is then again pulled upwardly by the spring 33^a, the arm 32^a operates to rock the dog slightly to the right 25 (as viewed in Fig. 7) so that the dog, as it again rises, will not go up in front of the tooth 57^a as shown by the solid lines in Fig. 7, but will be caught by the top of the tooth and arrested in the position shown by the broken lines in this figure. When in 30 this position, obviously the tooth will not be engaged by the dog so that the table may be moved to the left and as it is so moved the dog will slip into the next notch because of the pull of the spring and will engage the 35 next tooth 58^a on the rack bar. The operation of the parts thus far described should now be clear. I will assume that the rack-bar 24^a, having its teeth set one inch apart, 40 is being used and that the vernier adjustment is at neutral. The table is then moved to the left in any desired manner whereupon the dog 25^a will engage the tooth 57^a of the rack bar 24^a. A punching operation is 45 then performed. The arm 52 is then raised in any desired manner to rock the shaft 50 to raise the arm 51^a to rock the lever 28^a to lower the dog 25^a so that it will become disengaged from the tooth 57^a. The arm 52 is 50 then released, whereupon the spring 33^a will again raise the dog 25^a, but rock it slightly to the right (see Fig. 7) so that as it rises it will engage the top of the tooth 57^a. The table is then pushed to the left whereupon 55 the dog 25^a will ride into the next notch and be engaged by the next succeeding tooth 58^a thus giving a spacing of one inch whereupon another punching operation is performed. This process is repeated throughout the operative length of the rack-bar 24^a 60 so that a series of punching operations, exactly one inch apart, is performed upon the material carried by the table.

I will now describe the vernier adjustment, or means for spacing the punching

operations at intervals of a length lying between the intervals of two rack-bars. The dogs 25^a to 25^f are mounted in a block formed of seven plates 60 arranged on edge and suitably spaced apart and bolted together. This entire block carrying the dogs is substantially cubical in shape and adapted to slide longitudinally in the guides 61. Three of the plates 60 have forwardly projecting extensions 62 which are joined together at their forward ends by a plate 63, the forward end of which is pivotally attached to the transverse lever 64 by means of the pin 65. 66 indicates a substantially circular plate flattened at two sides as indicated by 67. This plate is slidably supported by means of the hangers 68 on the guide rods 69. The lever 64 is attached to the plate 66 at one end by means of the link 70 and at the other end by means of the threaded rod 71. This threaded rod is provided in order to give a method of adjusting the position of the attachment of the ends of the extensions 62 to the plate 66. In normal operation the screw-threaded rod 71 is set accurately and allowed to remain so. It will be seen then that the extensions 62 are attached to the plate 66 and that this plate 66 is slideable on the guides 69. The extensions 62, as has been stated before, 95 carry the block formed of the plate 60 in which the dogs 25^a to 25^f are mounted. As has been stated, this block is also slideable longitudinally. It will be seen therefore that if the plate 66 is stationary, the spacing on the work will correspond exactly to the spacing of the teeth on the rack-bar being used. If, however, the plate 66 slides forwardly at each punching operation, the 100 spacing given will be the spacing of the teeth on the rack-bar plus the distance that the plate 66 slides forward at each operation. 105

This will follow because if the plate moves forward it will also carry the block in which the dogs are mounted and thus give a longer space than the interval between the teeth on the rack-bar. For example, assuming again that the rack-bar 24^a is being used and that the teeth on this bar are spaced one inch apart, it will be seen that if the plate 66 is stationary, the punching operations will be one inch apart. If, however, after each punching operation, the plate 66 moves forward (that is, in the direction of the movement of the table) $\frac{1}{64}$ of an inch, the dog 25^a, at each punching operation, will move forward $\frac{1}{64}$ of an inch with the result that the distance between the holes punched will be $1\frac{1}{64}$ inches. 115

The following means are provided for so moving the plate 66 forward any desired distance at each punching operation; or for setting the vernier adjustment at neutral so that the punching operations will corre- 120 125 130

spond exactly to the spacing of the teeth on the rack-bar, the plate 66 not moving at all. Centrally arranged in the plate 66 is a pivot pin 70 carrying on its lower end below the plate 66 a generally transversely arranged guide 71. Slidably mounted within the guide 71 is a block 72 pivotally mounted by means of a pivot pin 73 to another block or shoe 74 adapted to slide on the transversely arranged rails 75. Between the rails 75 is a screw 76 extending through the block 74. The rails 75 are rigidly mounted on the base plate 77. It is obvious that when the guide 71 is parallel to the rails 75, rotation of the screw 76 will move both of the blocks 72 and 74 transversely of the device without causing any relative movement between the plate 66 and the base 77. If, however, the guide 71 is turned, as shown in Fig. 10, so that it is not parallel with the rails 75, rotation of the screw 76 will move the blocks 72 and 74 transversely along the length of the screw 76. Since the rails 75 are rigidly mounted, this movement of the blocks will be exactly transversely of the device. If the guide 71 is slightly twisted so that it does not lie exactly transversely of the device, movement of the blocks 72 in this guide will cause a corresponding movement of the plate 66 longitudinally of the device. For example, if the guide 71 is in the position as shown in Fig. 10, movement of the blocks 72 from left to right caused by rotation of the screw 76 will move the guide 71 and consequently the plate 66 forwardly. Rotation of the screw 76 is obtained in the following manner. This screw has mounted on its end (see Fig. 9) a pinion 80 meshing with an intermediate pinion 81 which in turn is adapted to be driven by a pinion 82 on a shaft 83 which has another pinion 84 on its other end adapted to mesh with the rack-bar 23 on the table 20. It will be seen, therefore, that movement of the table 23 will cause consequent rotation of the screw 76. As has been stated, if the guide 71 is arranged exactly transversely of the table and parallel with the screw 76, such rotation of the screw will cause no movement of the plate 66. If, however, it is twisted or turned, for example, to the position shown in Fig. 10, such rotation of the screw 76 caused by each forward movement of the table will cause a corresponding forward movement of the plate 66 and dog 25 corresponding to the position of the guide 71. The rear end of the guide 71 has attached to it a plate 90 bent upwardly and hooked over the circular edge of the plate 66. The forward end of the guide 71 has attached to it a clamp 91 provided with a screw 92 adapted to be screwed down against the upper surface of the plate 66 in order to hold the guide 71 in the desired position. Attached to the clamp 91 is a U-shaped mem-

ber 93 lying under the hexagonal end of the bar 37. This U-shaped member 93 carries a wire 94 lying over the hexagonal face 38^a. Each of the faces 38^a to 38^f has suitable markings with which the wire 94 may be made to register. These markings are so spaced as to show the exact spacing which the machine will give. It is to be noted that with this adjustment a very fine and accurate spacing may be obtained. For example, the wire 94 may travel over markings on the face 38^a covering a distance of more than two feet. Assume that the face 38^a indicates, as has been stated before, that a rack-bar with a spacing of one inch is being used. If the wire 94 is in the center of the face 38^a, or in neutral, so that rotation of the screw 76 will cause no movement of the plate 66, it is obvious that the spacing will be one inch. The parts may be so made that if the wire 94 is moved a distance of one foot on the face 38^a, the spacing will be increased to 1½ inches. It is obvious then that at intermediate points throughout this one foot movement of the wire 94, the spacing will vary from one inch to one and one half inches. In other words, an adjustment of the wire 94 through a distance of one foot will make a variation in the spacing of only one-half-inch. It will be seen therefore that a very fine and accurate adjustment of the spacing may be obtained.

It is to be noted that swinging of the guide 71 in the other direction beyond the neutral point will cause a slight backing up of the dog 25^a at each movement of the table so that the interval between the punching operations will be correspondingly shorter than the interval between the teeth of the rack-bar.

While I have shown and described certain embodiments of my invention, it is to be understood that it is capable of many modifications. Changes, therefore, in the construction and arrangement may be made without departing from the spirit and scope of the invention as disclosed in the appended claims in which it is my intention to claim novelty inherent in my invention as broadly as possible in view of the prior art.

What I claim as new, and desire to secure by Letters Patent, is:

1. A device of the character described comprising; a slidably mounted table; a rack-bar attached to the table; a dog arranged in connection with the rack-bar, whereby the dog will engage the successive teeth of the rack-bar upon successive movements of the table; and means for moving the dog in a direction parallel to the movement of the table, a predetermined distance at each movement of the table.

2. A device of the character described comprising; a slidably mounted table; a plurality of rack bars attached to the table,

each having teeth spaced at different intervals; a plurality of dogs, one dog corresponding to each rack-bar; means whereby any one dog may be moved into operative position to engage successive teeth of the corresponding rack-bar upon successive movements of the table; and means for moving the operative dog in a direction parallel to the movement of the table, a predetermined distance at each movement of the table.

3. A device of the character described comprising; a slidably mounted table; a plurality of rack-bars attached to the table; a plurality of dogs, one corresponding to each of the rack-bars; and means for moving any one dog into operative position to engage successive teeth of the corresponding rack-bar upon successive movements of the table, 15 said means including a lever having one end connected to the dog and a rotatable rod arranged adjacent said lever and provided with a flattened surface, said flattened surface permitting movement of said lever to 20 allow the dog to move into operative position.

4. A device of the character described comprising; a slidably mounted table; a plurality of rack-bars attached to the table; a plurality of dogs, one corresponding to each rack-bar; a slidably mounted block carrying said dogs; and means whereby any one of said dogs may be moved into operative position to engage successive teeth of the corresponding rack-bar upon successive movements of the table.

5. A device of the character described comprising; a slidably mounted table; a plurality of rack-bars attached to the table; a plurality of dogs, one corresponding to each rack-bar; a slidably mounted block carrying said dogs; a rotatable shaft mounted in said block; a plurality of pivoted levers mounted in said block, one for each dog, each having one end attached to its corresponding dog; and a plurality of flattened places on said rotatable rod, one corresponding to each of said pivoted levers whereby when said flattened place is adjacent a pivoted lever said corresponding pivoted lever is permitted to swing to allow the corresponding dog to move into operative position.

6. A device of the character described comprising; a slidably mounted table; a rack-bar attached to the table; a block arranged adjacent the rack-bar and adapted to slide in a direction parallel with said rack-bar, said block carrying a dog adapted to engage successive teeth of the rack-bar upon successive movements of the table.

7. A device of the character described comprising; a slidably mounted table; a rack-bar attached to the table; a slideable block arranged adjacent the rack-bar; a dog carried by the said block and adapted for

movement therein to engage and disengage the teeth on the rack-bar; spring means carried by the block tending to pull the dog into engagement with the teeth of the rack-bar; and means for holding said dog in 70 inoperative position where it will not engage the teeth of the rack-bar.

8. A device of the character described comprising; a slidably mounted table; a rack-bar attached to the table; a block slidably mounted adjacent the rack-bar; a dog carried by said block and adapted for movement therein to engage or disengage the teeth of the rack-bar; spring means tending to move the dog into position to engage 80 the teeth of the rack-bar; a pivoted lever carried by said block having one end attached to the dog; and a bar rotatably mounted in said block and adapted to engage said lever to move the same to hold 85 the dog away from the rack-bar to cause it to disengage the teeth thereof, said bar having a flattened part adapted to accommodate said pivoted lever to permit the dog to move toward the rack-bar to engage the 90 teeth thereof.

9. A device of the character described comprising; a slidably mounted table; a rack-bar attached to the table; a dog arranged in connection with the rack-bar, 95 whereby the dog will engage successive teeth of the rack-bar upon successive movements of the table; and means operated by the table for moving the dog in a direction parallel to the movement of the table, a predetermined distance at each movement of the 100 table.

10. A device of the character described comprising; a slidably mounted table; a rack-bar attached to the table; a dog arranged in connection with the rack-bar, whereby the dog will engage successive teeth of the rack-bar upon successive movements of the table; means for moving the dog in a direction parallel to the movement of the table a predetermined distance at each movement of the table, said means including two blocks connected together, one mounted on a screw arranged transversely of the table, and the other slidably mounted in a guide connected to the dog; and means for varying the angularity between said transversely arranged screw and said guide.

11. A device of the character described comprising; a slidably mounted table; a rack-bar attached to the table; a dog arranged in connection with the rack-bar, whereby the dog will engage successive teeth of the rack-bar upon successive movements of the table; means for moving the dog in a direction parallel to the movement of the table a predetermined distance at each movement of the table, said means including two blocks connected together, one mounted on a screw arranged transversely of 120 125 130

the table, means for rotating said screw, and the other block slidably mounted in a guide connected to the dog; and means for varying the angularity between said transversely arranged screw and said guide.

12. A device of the character described comprising; a slidably mounted table; a rack-bar attached to the table; a dog arranged in connection with the rack-bar, whereby the dog will engage successive teeth of the rack-bar upon successive movements of the table; means for moving the dog in a direction parallel to the movement of the table a predetermined distance at each movement of the table, said means including two blocks connected together, one mounted on a screw arranged transversely of the table, means operated by the table for rotating said screw, and the other block slidably mounted in a guide connected to the dog; and means for varying the angularity between said transversely arranged screw and said guide.

13. A device of the character described comprising; a slidably mounted table; a rack-bar attached to the table; a slidably mounted block arranged adjacent the rack-bar; a dog carried by said block and adapted to engage successive teeth of the rack-bar upon successive movements of the table; and means for moving the dog in a direction parallel to the movement of the table a predetermined distance at each movement of the table, said means including a pair of blocks connected together, one of said blocks mounted on a transversely arranged screw, the other block slidably mounted in a guide connected to the block carrying the dog, and means for varying the angularity between said guide and said transversely arranged screw.

14. A device of the character described comprising; a slidably mounted table; a rack-bar attached to the table; a slidably mounted block arranged adjacent the rack-bar; a dog carried by said block and adapted to engage successive teeth of the rack-bar upon successive movements of the table; and means for moving the dog in a direction parallel to the movement of the table a predetermined distance at each movement of the table, said means including a pair of blocks connected together, one of said blocks mounted on a transversely arranged screw, means for rotating said screw, the other block slidably mounted in a guide connected to the block carrying the dog, and means for varying the angularity between said guide and said transversely arranged screw.

15. A device of the character described comprising; a slidably mounted table, a rack-bar attached to the table; a slidably mounted block arranged adjacent the rack-bar; a dog carried by said block and adapted to engage successive teeth of the

rack-bar upon successive movements of the table; and means for moving the dog in a direction parallel to the movement of the table, a predetermined distance at each movement of the table, said means including a pair of blocks connected together, one of said blocks mounted on a transversely arranged screw, means operated by the table for rotating said screw, the other block slidably mounted in a guide connected to the block carrying the dog, and means for varying the angularity between said guide and said transversely arranged screw.

16. A device of the character described comprising; a slidably mounted table; a plurality of rack-bars attached to the table; a slidably mounted block arranged adjacent the rack-bars; a plurality of dogs carried by said block, one corresponding to each rack-bar; means for moving any one of said dogs into operative position to engage successive teeth of the corresponding rack-bar upon successive movements of the table; and means for moving the operative dog in a direction parallel to the movement of the table a predetermined distance at each movement of the table, said means including a pair of blocks connected together, one of said blocks mounted on a transversely arranged screw, the other block slidably mounted in a guide connected to the block carrying the dog, and means for varying the angularity between said guide and said transversely arranged screw.

17. A device of the character described comprising; a slidably mounted table; a plurality of rack-bars attached to the table; a slidably mounted block arranged adjacent the rack-bars; a plurality of dogs carried by said block, one corresponding to each rack-bar; means for moving any one of said dogs into operative position to engage successive teeth of the corresponding rack-bar upon successive movements of the table; and means for moving the operative dog in a direction parallel to the movement of the table, a predetermined distance at each movement of the table, said means including a pair of blocks connected together, one of said blocks mounted on a transversely arranged screw, means for rotating said screw, the other block slidably mounted in a guide connected to the block carrying the dog, and means for varying the angularity between said guide and said transversely arranged screw.

18. A device of the character described comprising; a slidably mounted table; a plurality of rack-bars attached to the table; a slidably mounted block arranged adjacent the rack-bars; a plurality of dogs carried by said block, one corresponding to each rack-bar; means for moving any one of said dogs into operative position to engage successive teeth of the corresponding rack-bar upon successive movements of the table; and means

for moving the operative dog in a direction parallel to the movement of the table, a predetermined distance at each movement of the table, said means including a pair of 5 blocks connected together, one of said blocks mounted on a transversely arranged screw, means operated by the table for rotating said screw, the other block slidably mounted in a guide connected to the block carrying the dog, and means for varying the angularity between said guide and said transversely arranged screw.

19. A device of the character described comprising; a slidably mounted table; a 15 rack-bar attached to the table; a dog support arranged adjacent the rack-bar; a dog mounted in said dog support and adapted for movement therein to disengage or engage the teeth of the rack-bar; spring means 20 tending to move said dog in said dog support toward the rack-bar to engage the teeth thereof; said dog support also permitting slight movement of the dog therein in a direction parallel to the movement of 25 the table.

20. A device of the character described comprising; a slidably mounted table; a rack-bar attached to the table; a dog support arranged adjacent the rack-bar; a dog 30 carried by said dog support and adapted for movement therein to engage or disengage the teeth of the rack-bar and also adapted for slight movement therein in a direction parallel to the movement of the table; and 35 spring means tending to pull the dog toward

the rack-bar to engage the teeth thereof, said means also tending to move said dog in a direction opposite to the forward movement of the table.

21. A device of the character described comprising; a slidably mounted table; a rack-bar attached to the table; a dog support arranged adjacent the rack-bar; a dog carried by said dog support and adapted for movement therein to engage or disengage 40 the teeth of the rack-bar and also adapted for slight movement therein in a direction parallel to the movement of the table; and spring means tending to pull said dog in 45 said dog support in a direction opposite to the forward movement of the table.

22. A device of the character described comprising; a slidably mounted table; a rack-bar attached to the table; a dog support arranged adjacent the rack-bar; a dog 50 mounted in said dog support and adapted for movement to engage or disengage the teeth of the rack-bar and also adapted for movement in said dog support in a direction parallel to the movement of the table; 55 spring means tending to pull said dog toward the rack-bar to engage the teeth thereof; and means tending to pull said dog in said dog support in a direction opposite to the forward movement of said table. 60

In witness whereof, I have hereunto set my hand and seal this 15th day of October, 1923.

EDWIN G. DANIELS. [L. S.]
